US00D899499S

(12) **United States Design Patent** (10) **Patent No.:** **US D899,499 S**
Cohen et al. (45) **Date of Patent:** **** Oct. 20, 2020**

(54) **SMART GLASSES**

(71) Applicant: **Lucyd Ltd.**, Singapore (SG)

(72) Inventors: **David Cohen**, Aventura, FL (US);
Clifford Gross, Miami, FL (US);
Harrison Gross, North Miami, FL (US)

(73) Assignee: **Lucyd Ltd.** (GB)

(**) Term: **15 Years**

(21) Appl. No.: **29/684,669**

(22) Filed: **Mar. 22, 2019**

(51) LOC (12) Cl. **16-06**

(52) U.S. Cl.

USPC **D16/309**

(58) **Field of Classification Search**

USPC D16/101, 300, 301, 303, 310, 311, 312, D16/313–316, 319, 320, 325–326, 328, D16/329, 330, 331, 332, 334, 335, 340, D16/341, 342; D29/109–110; D14/372; 351/41, 44, 45–48, 51–52, 62, 158, 92, 351/103–123, 140–153, 63, 59

CPC A63B 33/00; A63B 33/002; G02C 1/00; G02C 1/02; G02C 1/04; G02C 1/06; G02C 5/02; G02C 5/04; G02C 5/08; G02C 5/12; G02C 5/22; G02C 9/00; G02C 9/02; G02C 9/04; G02C 11/00; G02C 11/02; G02C 2200/00; G02C 2200/02; G02C 11/04; G02C 5/008; G02C 5/14; G02C 5/16; G02C 5/146; G02C 5/2254; G02C 2200/08; G02C 2200/22; A61M 2021/0044; G02B 27/2228

(57) **CLAIM**

The ornamental design for smart glasses, as shown and described.

DESCRIPTION

The patent or application file contains at least one drawing executed in color. Copies of this patent or patent application with color drawing(s) will be provided by the Office upon request and payment of necessary fee.

FIG. 1 is a front top perspective view showing our new design;

FIG. 2 is a rear top perspective thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view.

1 Claim, 8 Drawing Sheets
(8 of 8 Drawing Sheet(s) Filed in Color)
